DEVICE FOR CONSTRICTING THE THREAD BALLOON IN RING SPINNING AND RING DOUBLING FRAMES

Ernst Reissmuller, Hof (Saale), Germany, assignor to Hermann Ebner & Co., Hof (Saale), Germany

Application March 19, 1956, Serial No. 572,386

Claims priority, application Germany March 31, 1955

10 Claims. (Cl. 57—106)

The invention relates to a device for constricting the thread balloon, and which consists of a thread balloon constricting hoop carried by support legs, wherein the support legs are fixed to a flat substantially circular ring which is secured on the ring rail and is held by the spinning or doubling ring, and the said support legs may serve if so required as fly cleaners for the travellers, being suitably constructed and arranged for this purpose.

Thread balloon constricting hoops are known in many types of construction and arrangement. If a plurality of restricting hoops made of steel wire are used spaced at a certain distance from one another, the lower hoop is generally moved synchronously with the ring rail and the upper hoop is moved in similar manner to the thread guide eyelet. The constricting hoops are then fixed to horizontal rails or to vertical bars, and supports which are articulated in hinged fashion. This plurality of parts arranged on or behind the ring rail have a disturbing effect during operation and also tend to collect dirt and fly, and thus they are a source of constant trouble.

It has also already been proposed to fix at least one constricting hoop to a support which is mounted near each or between two rings on the ring rail. This arrangement of supports has not been accepted at all in practice since each part fixed to the ring rail makes it difficult to keep clean and hinders the work of the operator in general.

In the case of all hitherto known arrangements, it is necessary at the time of assembly and continuously during operation, to centre the hoops i. e. to arrange them so as to be exactly co-axial with the spinning spindle. In practice, the spindle will always be aligned in accordance with the ring; then the thread guide eyelet and the constricting hoops are adjusted with the help of special tools, which is quite a difficult operation.

The object of the present invention is to free the ring rail of all parts which are provided for fixing the constricting hoops and tend to collect dust and fly, and to make the time-wasting centering of constricting hoops unnecessary.

With this object in view, the thread balloon constricting hoop is carried by one or more support legs which are fixed to a flat, substantially circular disc. The internal diameter of this disc corresponds to the ring rail bore for receiving the rings; it bears on the ring rail under the ring and is held fast thereby without further means being necessary.

In this way the device with the constricting hoop is constrainedly centred by the spinning or doubling ring, and no devices and auxiliary tools are required for accurate setting of the constricting hoops.

2

But also, in order to render unnecessary the provision of fly removers for the traveller e. g. on cotton and artificial staple fibre ring spinning frames, and to make it possible to dispense with such fly removers, the support legs which carry the constricting hoop are constructed themselves as fly removers.

According to the invention preferably two support legs are provided; alternatively it is possible to provide only one support leg or more than two. If two support legs are used it is advantageous to fix them to the flat disc offset by approximately 180° relatively to one another.

The fastening means for securing the constricting hoop to the support legs may be fixed or releasable or may be vertically adjustable. This can be achieved by means of fixing bolts which are screwed in through slots or holes in the support legs and into the hoops, or by means of straps or claws or the like which serve for guiding the support legs, and clamping screws for fixing the hoop in the desired position.

15 20 25 In order to reduce the friction of the thread against the inner surface of the constricting hoop the said surface is preferably of curved construction so that, in the case of a hoop which is outwardly curved, the thread bears against only the top and bottom inner edges of the hoop or, if the hoop is inwardly curved, the thread bears against a short section in the middle of the curved portion.

20 25 30 35 In order to make it possible to insert the thread quickly and easily into the inside of the constricting hoop and to prevent it from escaping accidentally from the said hoop, the latter is formed with a preferably oblique slot which is advantageously widened considerably at one end and whose inner edge which the thread passes by last during its travel, is sharply rounded-off or bevelled. Alternatively, it is possible to bend this edge slightly outwards, which has the same advantageous result. The inclination of the slot relatively to the vertical depends on the position of the thread and the type of twist. The slot must form at least an acute angle with the thread.

30 35 40 45 The circular discs, which bear against the ring rail and carry the support legs of the constricting hoop, are expediently secured against undesirable rotation. There are various possible ways of doing this, for example the outer periphery of the disc can be made to deviate from a perfectly circular form in such manner that the discs arranged adjacent one another on the ring rail prevent each other from rotating. Another method is to fix the discs by screws or in similar fashion to the ring rail.

40 45 50 55 Fly removers for the traveller are known and are generally screwed to the ring rail at such a distance beside the spinning ring that their sharp edge directed in the opposite sense to the movement of the traveller strips off any fly which may adhere to the said traveller without impairing the travel thereof. In order that the support legs can fulfil their particular task of acting as fly removers for the traveller, they are sharpened at their edge, at least at the level of the traveller, and more particularly at the edge facing towards the ring and opposed to the direction of travel of the traveller, and they are set in accordance with the usual position of fly removing devices.

A few specially preferred constructional examples of the subject of the invention which will now be described in more detail, are illustrated in Figs. 1 to 14.

Fig. 1 is a perspective view of the device,

Fig. 2 shows the device fixed to the ring rail by the ring,

Figs. 3 to 6 show different methods of fixing the constricting hoop to the support legs.

Figs. 7a and 7b show two different profiles for the constricting hoop.

Figs. 8 to 11 show different constructional examples for the slot through which the thread can be introduced into the constricting hoop, and

Figs. 12 to 14 show devices which prevent the rotation of the discs on the ring rail.

As may be seen from Fig. 1, the device consists of the flat substantially annular disc 1 to which the support legs 2 are fitted preferably by welding. The support legs 2 carry the thread balloon constricting hoop 3 which can be connected to the said legs fixedly or else releasably by means of screws 4. It is expedient, for example, to provide at the upper part of the support legs 2 a number of holes 5 so that the position of the constricting hoop in the vertical sense may be varied or so that the same device can be used for different heights of stroke of the ring rail. To allow insertion of the thread, the ring comprises in the usual manner a sloping slot 6 or, as is shown in Fig. 2, a vertical slot 6'.

Fig. 2 shows the arrangement of the device on the ring rail 9; the internal diameter of the disc 1 corresponds to the bore provided in the ring rail 9 for the rings 7. The disc 1 is supported between the ring rail 9 and the collar 8 which is generally provided on the ring. The screw 9' or a clamping device is provided as usual for fixing the ring; this screw or device holds the device according to the invention at the same time. Since the constricting hoop 3 is arranged coaxially with the disc 1 during manufacture, there is no need for an operation for centering the constricting hoop as would otherwise be necessary.

In order to fix the position of the circular discs 1 and to prevent rotation thereof on the ring rail 9, the outer periphery of the disc is made to deviate from the circular in such manner that the adjacently disposed discs prevent each other from rotating.

As Fig. 12 shows, the discs 1 are provided with two straight, parallel, diametrically oppositely disposed edges 1¹ at which the said discs contact one another.

Another example is illustrated in Fig. 13, wherein instead of straight edges the discs 1 comprise a recess 1³ and a diametrically opposite projection 1². The engagement of the projection 1² in the recess 1³ of the adjacent disc couples together all the discs of one row.

Both constructional examples have the advantage that a disc can be removed without wasting any time on releasing fastening means.

Another possible method of preventing the discs from rotating is—as is shown in Fig. 14—to fix the discs 1 to the ring rail 9 by means of screws 29. Instead of screws, other similar means can also be used.

In order to clean the traveller from any spinning fly which may adhere thereto, the edges 10 of the support legs 2 are sharpened and are arranged in the position of fly removers with respect to the traveller.

According to Fig. 3 the hoop 3¹ is fixed to the support leg 2¹ by means of straps 11 which carry a clamping screw 12.

In the construction according to Fig. 4, the support legs 2² are guided between claws 13. Clamping is carried out by means of the bolts 15 which are screwed into the tapped hole 14 in the support legs 2².

Fig. 5 shows a further method of fixing. The hoop 3³ has a thickened portion 16 in the region of the tapped hole 17 for receiving the fastening bolts 18 which extend through the slots 19 in the support legs 2³.

In Fig. 6, the clamping screw 20 is mounted tangentially to the hoop 3⁴ in the strap 21.

If the constricting hoop 3⁵ is profiled in the manner illustrated in Fig. 7a, the thread 22 bears against only a short section on the curved inner side of the constricting hoop 3⁵.

If the hoop 3⁶ is curved in the outward direction as

shown in Fig. 7b, the thread 22¹ in practice bears against only the top edge 23 and the bottom edge 24 of the said hoop 3⁶.

As is shown in Figs. 8 and 9, the insertion slot 6¹ or 6² is widened in the region of the lower edge 25 or 25¹ of the constricting hoop 3⁷ or 3⁸, so that the thread can be inserted more easily.

As can be seen from Fig. 10, when the thread 22² is travelling in the direction represented by the arrow 26 the inner edge 27 of the slot 6³ in the hoop 3⁹ is rounded to a considerable extent. Fig. 11 shows another possibility of achieving the same effect; according to this figure, the edge 28 of the hoop 3¹⁰ is bent slightly outwards.

The devices according to the invention make it possible to constrict the thread balloon to such an extent that even with narrow spindle spacing and with relatively high spindle speeds, the balloon has no disturbing effect. The thread is no longer subjected to a constant variation in tension, but travels smoothly and quietly. Thread breaks are considerably reduced and wear on the spinning and doubling rings is completely uniform and is substantially reduced.

A further very important advantage consists in that when a device according to the invention is used, considerably lighter travellers can be employed and the rotational speed of the spindles can be substantially increased. In the most disadvantageous case, the capacity of a machine can be increased by about 15 to 20%, and in normal cases even more.

Finally, by reason of the simple construction of the device according to the invention, it may be mentioned as a further advantage that the said device can be manufactured very economically, and is simple to assemble and demount, no skilled operator being required for this purpose.

What I claim, and desire to secure by Letters Patent is:

1. In a spinning machine provided with ring spinning and doubling frames and a traveller, a device for constricting the thread balloon, comprising in combination, a ring rail, a plurality of annular openings in said ring rail, a plurality of annular discs, each secured to said rail about each said opening thereof and aligned with each said respective opening, a plurality of spinning rings in said ring rail, each of said spinning rings respectively securing each of said discs to said rail about one of each said respective openings, at least one pair of support legs, each of said pair of legs having one of its ends secured to each of said circular discs, and a thread balloon constricting hoop secured to each of the other ends of each of said pair of support legs.

2. The device according to claim 1, wherein each of said constricting hoops is secured to said ends of said support legs coaxially with respect to said circular disc.

3. The device according to claim 2, wherein each of said spinning rings is formed with an annular, outwardly extending collar portion for clamping each of said annular discs respectively to said ring rail.

4. The device according to claim 3, wherein said pair of support legs is formed with sharply beveled edges on the sides thereof, directed oppositely to the movement of the traveller, for removing fly.

5. The device according to claim 1, wherein each of said constricting hoops is curved inwardly about its circumference.

6. The device according to claim 1, wherein each of said constricting hoops is curved outwardly about its circumference.

7. The device according to claim 1, wherein said annular discs are disposed on said rail member adjacent to one another, and means provided in said discs for preventing the rotation thereof on said rail member.

8. The device according to claim 7, said means for preventing the rotation of said discs consisting of diametrically opposed flat portions on the annular circumference.

of each of said discs, said flat portions abutting against one another.

9. The device according to claim 7, wherein said means consist of projections extending from the outer periphery of each of said rings and diametrically opposed thereto recesses, each said projection being received in each said recess of an adjoining ring disc respectively.

10. The device according to claim 7, wherein said adjacent ring discs are secured to said ring rail by means of screw fasteners.
